(57) **CLAIM**

The ornamental design for a vertical wall reveal, as shown and described.

DESCRIPTION

FIG. 1 is a perspective view of a vertical wall reveal, showing the new design.

FIG. 2 is a second perspective view of the vertical wall reveal of FIG. 1.

FIG. 3 is a first side view of the vertical wall reveal of FIG. 1.

FIG. 4 is a second side view of the vertical wall reveal of FIG. 1.

FIG. 5 is a front view of the vertical wall reveal of FIG. 1.

FIG. 6 is a back view of the vertical wall reveal of FIG. 1.

FIG. 7 is a top view of the vertical wall reveal of FIG. 1; and,

FIG. 8 is a bottom view of the vertical wall reveal of FIG. 1.

The broken lines shown in FIGS. 1, 2, 5, 7 and 8 illustrate portions of the vertical wall reveal that form no part of the claimed design.

1 Claim, 6 Drawing Sheets
